MARVIN L. CHAPPELL, OF INGLEWOOD, AND GEORGE J. ZISER, OF LOS ANGELES, CALIFORNIA, ASSIGNEES, BY MESNE ASSIGNMENTS, TO STANDARD OIL COMPANY OF CALIFORNIA, OF SAN FRANCISCO, CALIFORNIA, A CORPORATION OF DELAWARE

PROCESS OF PURIFYING PETROLEUM DISTILLATES

Application filed July 20, 1925. Serial No. 44,757.

This invention relates to a process of purifying petroleum distillates. Hitherto, the treatment of petroleum distillates such as lubricating distillates for the production of finished products such as lubricating oil, has been accomplished by the well known sulfuric acid treatment followed by a neutralizing with alkali and subsequent clarification with a decolorizing clay. Such process for the treatment of oils is unsatisfactory in that it involves the loss of considerable quantities of valuable hydrocarbons which are removed by this acid treatment, being combined with sulfuric acid to form a sludge and not recoverable. These losses are exceptionally high where large quantities of strong acid are used, such as in the manufacture of medicinal oil, due to oxidation, sulfonation or other chemical action upon the hydrocarbons. This treatment also requires considerable quantities of sulfuric acid, only a part of which can be recovered. An object of the present invention is to provide a process for purifying petroleum oils by which this loss of material due to oxidation, sulfonation or chemical action may be avoided; by which the reagent used for effecting the purification can be substantially completely recovered and reused, and by which the cost of treatment or purification of petroleum oils may be decreased.

Another object of the present invention is to provide a process for treating petroleum oils by which the oils may be separated into products having different viscosities by means of a solvent.

The present invention embraces the discovery that, although aniline and petroleum oil are mutually soluble when heated, upon cooling of a solution of aniline and petroleum oil, separation will take place into an aniline layer which retains in solution certain undesirable constituents of the petroleum oil, the body of the desired constituents of the petroleum oil separating from such layer. The constituents retained by an aniline solution at low temperatures are mainly asphaltic compounds, sulfur compounds or unsaturated bodies of high molecular weight. All of these constituents are undesirable in high-

grade lubricating oils or medicinal oils, but may be used to advantage in the manufacture of greases or other dark colored lubricants of high viscosity.

Thus, the present invention affords a physical means for separation of these undesirable constituents from high-grade lubricating oil while preserving the character of these constituents so that they may be utilized in the manufacture of other products, whereas the usual method of treating petroleum oils with sulfuric acid removes these constituents by chemically uniting therewith or otherwise chemically changing the same so that such constituents are rendered practically valueless or are difficult to dispose of in the oil refinery.

Various other objects, advantages and discoveries of the invention will be apparent from the following description of a preferred example of a process embodying the invention. For this purpose reference is made to the accompanying drawings, which illustrate diagrammatically an apparatus in which or by which the preferred method may be carried out.

In the drawing, 1 indicates a storage tank for aniline oil; 2 indicates a storage tank for untreated petroleum oil; 3 represents a cone-bottom tank provided with a coil 31 by which the contents of the tank may be heated or cooled; 4 and 5 designate steam stills for recovering aniline from the treated oil and the extracted oil; 6 is a cone-bottom tank for receiving the distillate from aniline stills 4 and 5; and 7 is a tank for receiving the extracted oil after the aniline has been removed therefrom; 8 represents a tank for receiving the treated lubricating oil after the aniline has been removed.

The process may be used on all petroleum distillates having initial boiling points of from 400° F., the process thus being adapted for the purification of all lubricating oil distillates and mineral seal oil, the latter being an oil employed as a light lubricant or a long-time burning illuminating oil.

In carrying out the preferred process, tank 3 is first charged with a desired quantity of petroleum oil from the storage tank 2 through

pipes 12 and 13. The desired volume of aniline is then charged into the tank from the aniline storage tank 1 through pipe 13. The relative amount of petroleum oil and aniline charged into the treater may vary widely, depending upon the character of petroleum oil to be treated and the degree of purification of treatment to be thereby effected. For example, an equal volume of aniline to that of the oil may be employed.

By means of the centrifugal pump 14, the aniline and oil are then thoroughly mixed by circulation, the oil being taken from the bottom and pumped into the top of the tank 3, valves 15, 16 and 18 being closed, valves 17, 37 and 38 being open. During this period of operation, the admixture is preferably heated, in order to effect or to secure a complete solution of the petroleum oil in the aniline; such heating may be accomplished by the addition of steam through coil 31 in tank 3. The temperature to which the admixture or solution should be heated varies with the character of distillate used, and the proportions of aniline and petroleum oil used, however, we have found that with an equal volume of aniline, the average lubricating oil distillates are soluble at about a temperature of 170° F. Subsequent to such complete solution of the petroleum oil and aniline while continuing the circulation of the solution, the solution is cooled down, preferably by the introduction of cold water through coil 31 until separation takes place. The temperature to which the solution should be cooled to effect such separation also varies with the character of petroleum oil, the relative amounts of petroleum oil and aniline employed, and the degree of purification desired. Under ordinary conditions and with the average lubricating oil distillate and equal proportions of lubricating oil and aniline, we have found that 70° to 80° F. is a suitable temperature to use, however, at lower temperatures a more selective solubility is obtained.

After the desired temperature has been attained, the circulation is discontinued and the mixture is then allowed to stand at rest until complete separation of the oil and aniline layers has taken place. The aniline layer, which is of much heavier specific gravity than the oil, readily settles to the bottom and is withdrawn from tank 3 and introduced into steam still 4 through pipe 21, valves 17 and 20 being closed and 18 and 19 being open.

The charge in still 4 is distilled with steam, the vapors of aniline and steam passing through line 25 into a condenser 9, and after condensation the liquids are collected in receiver 6 passing thereto through pipe 26. After the aniline has been completely removed from the material charged in the still 4, the residue in the still 4, which con-

sists of the oil extracted from the original distillate, is introduced in the tank 7 through line 27.

The treated lubricating oil in tank 3 after removal of the aniline containing the extracted or purified oil contains a small percentage of aniline, which is readily removed by steam distillation in still 5. For such purpose, such treated lubricating oil is introduced into still 5 through lines 21 and 32, valves 17 and 19 being closed, valve 20 being open. Here such oil is subjected to steam distillation, causing the aniline and steam to pass through vapor line 22 into condenser 10 and the condensed aniline and steam is introduced into receiver 6 through line 33. After the aniline has all been removed by such distillation of the oil in still 5, such oil is then transferred to storage tank 8 through pipe 23.

Receiver 6 contains the aniline and condensed steam from stills 4 and 5. The aniline and water may be separated by the addition of sufficient salt and agitation with air, the air being added through line 34 controlled by valve 35. After the aniline has been salted out from the water, the water is drawn off through pipe 36, valves 29 and 35 being closed, valve 30 being open. The recovered aniline is then again introduced into storage tank 1 through pipe 11, through closing of valve 30 and opening of valve 29. This completes the cycle of operation and the aniline is then again ready for use in further treatment.

While the above description serves to illustrate the method of applying the aniline to the oil in a single treatment, we find that it is sometimes necessary to apply two or more portions of aniline to the oil in successive treatments in order to obtain the desired purification. This can readily be accomplished by merely adding an additional portion of aniline to the oil in tank 3 after the separated aniline and extracted oil has been drawn off. The operation of circulating, heating, and cooling is carried out the same as described for the first aniline treatment. In this way, the oil may be treated with as much fresh aniline as is necessary to obtain the desired finished oil.

Furthermore, this treatment may be employed or carried out merely to effect part of the purification of the oil, and the oil after such treatment may be then further treated by sulfuric acid or clarified with clarifying or decolorizing clays, if desired. The process is of particular value in the manufacture of medicinal oils, as it affords a great saving of acid, since as much as eight pounds per gallon of fuming sulfuric acid is required, and less than fifty percent of the oil is obtained as finished product after this treatment, the remainder of the oil being combined with the acid in the form of sludge, which is practi-

cally valueless. By giving a preliminary treatment with aniline, followed by fuming acid, medicinal oil may be manufactured at a great saving, both in acid and in oil.

5 In the foregoing description, we have referred to aniline oil as the purifying reagent; however, it is understood that it is not intended to confine the method to the use of aniline oil, since other aromatic amines, such as the toluidenes, xylidenes, etc., having similar characteristics would also be effective.

10 Moreover, the process is not confined to the specific treatment described, as the treatment may be carried out at a temperature below 15 which the oil and aniline are mutually soluble, and may be carried out at temperatures as low as 15° F. and it is also understood that this process may be applied to an oil which has had a preliminary acid treatment.

15 20 It is to be understood that the invention includes all such modifications and substitutions as come within the scope of the appended claims.

We claim:-

25 1. The process of treating viscous high boiling point petroleum distillates, which comprises mixing aniline oil with the distillate, heating the mixture at a temperature sufficient to produce a homogeneous solution, 30 and then cooling the mixture to a temperature where the saturated constituents of the oil separate from the aniline and the other constituents remain dissolved by the aniline.

35 2. The process of treating viscous high boiling point petroleum distillates, having an initial boiling point of about 400° F., which comprises admixing such oil with aniline oil and heating the admixture to effect a homogeneous solution, then cooling the solution to 40 effect separation thereof into liquid oil and aniline oil containing unsaturated constituents of the petroleum oil in solution, and separating such liquids.

45 3. A process of treating viscous or lubricating stocks of petroleum oils for removal of the unsaturated constituents, which comprises admixing such distillates with approximately an equal volume of aniline oil and heating the admixture to a temperature of at 50 least 170° F. to effect a homogeneous solution, then cooling the solution to below 80° F. until the saturated hydrocarbons separate from the aniline oil and the unsaturated hydrocarbons, and separating such liquids.

55 4. A process of treating viscous or lubricating stocks of petroleum oils for the removal of the unsaturated constituents, sulfur, asphaltic and resinous compounds which comprises, admixing such distillates with approximately an equal volume of aniline oil and heating the admixture to a temperature of at 60 least 170° F. to effect a homogeneous solution, then cooling the solution to below 80° F. until the saturated hydrocarbons separate 65 from the aniline oil and the unsaturated hy-

drocarbons, sulfur, asphaltic and resinous compounds, and separating such liquids.

Signed at El Segundo, Calif., this 10th day of July, 1925.
